UNITED STATES PATENT OFFICE

148,776

DESIGN FOR A MULTIPLE DESK UNIT

Benton L. Fay, St. Joseph, Mich.

Application August 17, 1946, Serial No. 132,607

Term of patent 14 years

(Cl. D33—7)

To all whom it may concern:

Be it known that I, Benton L. Fay, a citizen of the United States, residing at St. Joseph, in the county of Berrien and State of Michigan, have invented a new, original, and ornamental Design for a Multiple Desk Unit, of which the following is a specification, reference being had to the accompanying drawing, forming part thereof.

The figure is a perspective view of a multiple desk unit showing my new design, the fronts of the three segments of the desk not illustrated being of the same design as the corresponding segment illustrated.

I claim:

The ornamental design for a multiple desk unit, as shown and described,

BENTON L. FAY.
